UNITED STATES PATENT OFFICE.

FREEMAN C. ROBINSON AND JOHN F. JACOBY, OF MINNEAPOLIS, MINNESOTA, ASSIGNORS TO AMERICAN BANK PROTECTION CO., OF MINNEAPOLIS, MINNESOTA, A CORPORATION.

MACHINE FOR MAKING VAULT-LININGS.

SPECIFICATION forming part of Letters Patent No. 781,365, dated January 31, 1905.

Application filed November 9, 1903. Renewed September 9, 1904. Serial No. 223,860.

To all whom it may concern:

Be it known that we, FREEMAN C. ROBINSON and JOHN F. JACOBY, of Minneapolis, Hennepin county, Minnesota, have invented certain new and useful Improvements in Machines for Making Vault-Linings, of which the following is a specification.

Our invention relates to a machine for making vault-linings to be used in connection with an electric burglar-alarm system.

The object of our invention is to provide a machine wherein the metallic surface sheets and the core of insulating material can be easily and quickly secured together, the sheets having been previously cut to the desired shape and size.

The invention consists generally of various constructions and combinations, all as herein-after described, and particularly pointed out in the claims.

In the accompanying drawings, forming part of this specification, Figure 1 is a plan view of a machine embodying our invention. Fig. 2 is a side elevation. Fig. 3 is a section on the line *xx* of Fig. 1. Fig. 4 is a section on the line *yy* of Fig. 2.

In the drawings, 2 represents a suitable frame whereon the operating parts of the machine are supported, and 3 is a horizontal feed-table arranged at the receiving end of said frame. The sheets of which each vault-lining is composed are placed upon the table 3, having previously been coated by dipping or by a brush with shellac.

The linings are made in sections varying in form and size, according to the vault where used, and each lining-section consists of two metallic sheets, preferably of ordinary sheet metal of suitable weight, and an interposed sheet of non-conducting material, preferably strawboard. The metallic sheets are coated with shellac on the inside. The strawboard sheet is coated on both sides and presents, therefore, a shellac surface to the contiguous surface of the metallic sheets.

On the table 3 is a sheet-metal covering 4,

and at the inner end of said table, supported in standards 5, is a guide or feed roller 6 and a series of gas-pipes 7 and 8, arranged in pairs one above another, the upper pipes being above the level of the table 3 and the lower pipes below the level of said table. These pipes lead to a gas-supply pipe 9, provided with suitable valves 10, and the pipes 7 are provided in their under surfaces with a series of perforations 11 opposite a number of corresponding perforations in the upper surface of the pipes 8. When therefore gas is admitted to these pipes and lighted, little jets of flame will be projected through the perforations 11, and these jets will meet at a point about midway between the pairs of pipes and substantially opposite the surface of the table 3.

Near the standards 5 we provide brackets 12, wherein pressure-rolls 13 and 14 are mounted. The roll 13 is fixed in its bearings, while the roll 14 is vertically movable, being normally held away from the surface of the roll 13 by coil-springs 15. Set-screws 16 are provided in the brackets 12 and arranged to engage the bearings of the roll 14 and press it toward the roll 13 against the tension of the springs 15. On the discharge side of the pressure-rolls is a table 17, whereon a closed stationary water-tank 18 is mounted, having a flat top and a flexible connection 19 with a similar movable tank 20. This movable tank is provided with an inlet-pipe 21, through which cold water is conducted into the tank 20 and flowing from thence through the pipe 19 to the tank 18 is discharged through a pipe 22. There is therefore a continuous stream of cold water flowing through the tanks and keeping their contacting surfaces cool at all times. The tank 20 normally rests upon the top of the tank 18, and to lift the tank 20 when it is desired to insert a section of the vault-lining beneath it we provide links 23, pivotally supported on cross-bars 24, secured to standards 25, connected with said movable tank by turnbuckles 26, by means of which said stationary tank can be adjusted vertically.

- To swing the said movable tank on its pivots and lift it away from the top of the stationary tank, we provide a bail 27, pivoted on said movable tank and connected to a rope 28, that 5 passes over pulley-blocks 29 to a suitable handle 30, that depends near the table 3 within convenient reach of the operator.
- Any suitable means may be provided for 10 operating the pressure-rolls; but we prefer to provide a driven shaft 31, having a pulley 32 and a worm 33, adapted to engage a gear 34, that is mounted on a shaft 35 and has a pinion 36 in position to engage a gear 37 on the shaft of the lower pressure-roll. An idle pinion 38 engages the pinion 36 of a gear 39 on the shaft of the upper pressure-roll.

The operation of the machine is as follows: The sheet-metal vault-sections having previously been coated on one side with shellac are 20 placed upon the table 3, with a sheet of insulating material that has been dipped in shellac between them. The sheets having been trimmed to the proper dimensions are fed forward by the operator between the pairs of 25 gas-pipes and through the tiny projecting gas-flames. As the sheets are slowly fed forward through the gas-jets the shellac will be softened, and as the sheets enter between the pressure-rolls they will be firmly pressed together, 30 the softened shellac causing them to adhere to each other and form, as it were, one homogeneous sheet. After leaving the pressure-rolls the sheet will pass upon the flat surface of the stationary tank, the movable tank having 35 been raised for that purpose, and the sheet having reached the desired position the operator will allow the movable tank to drop down to its normal position and flatten out the sheet and quickly cool its surface. The metallic 40 sheets will be insulated from each other and will be firmly attached to the intermediate insulating-sheet by the coatings of shellac thereon. As soon as the section is removed from between the tanks it is ready to be placed in 45 its proper position in the vault-lining.

We claim as our invention—

1. The combination, with a feed-table, of means for heating the upper and lower surfaces of sheet-metal sections thereon, pressure-rolls provided near said heating means and a flattening and cooling device whereto said sections are delivered from said rolls. 50
2. The combination, with a feed-table, of gas-pipes arranged in pairs near the same, some of said pipes being above the level of said table and others below, and all of them having holes or perforations in their contiguous surfaces, pressure-rolls provided near said pipes and a cooling device arranged on 55 the discharge side of said pressure-rolls.
3. The combination, with a feed-table, of means provided near the discharge side of said table and arranged to heat the surfaces of metal sheets fed forward from said table,

pressure-rolls whereto the sheets are delivered 65 after leaving said heating means, and a cooling device arranged on the discharge side of said pressure-rolls.

4. The combination, with a feed-table, of gas-pipes provided near the discharge side of 70 the same and having a series of perforations, said pipes being arranged above and below the level of said table to direct jets of flame upon the upper and under surfaces of material fed forward from said table, and pressure-rolls 75 provided near said pipes.

5. The combination, with heating means, of pressure-rolls provided near the same, a stationary water-tank having a flat top and a movable water - tank having a flat bottom 80 adapted to rest upon said stationary tank.

6. The combination, with a feed-table, of gas-pipes having a series of perforations and arranged near the discharge side of said feed-table, and above and below the level of the 85 same, pressure-rolls provided near said gas-pipes, a flat-topped stationary tank arranged near the discharge side of said rolls, and a flat-bottomed movable tank pivotally supported above said stationary tank and normally 90 resting thereon, and means within control of the operator for lifting said movable tank.

7. A machine of the class described comprising a table adapted to receive sheets placed one above another thereon and having their 95 contiguous surfaces coated with an adhesive agent with a non-conducting material between them, means for heating the surfaces of said sheets to soften the said adhesive agent, means for applying pressure to said sheets while said 100 adhesive agent is in a plastic condition, and a cooling device.

8. The combination, with a feed - table, adapted to receive metal sheets placed one above another, and having their contiguous 105 surfaces coated with an adhesive agent, with a non - conducting material between them, means for heating the surfaces of said sections to soften the said adhesive agent, means for applying pressure to said sheets, and 110 means for flattening the sheets after leaving said pressing means,substantially as described.

9. The combination, with a feed-table, of means for heating sheet-metal sections placed one above another thereon with a non-conducting material between them, the contiguous surfaces of said sheets being coated with an adhesive agent, and means for applying pressure to said sheets after leaving said heating means. 115

10. The combination, with means for heating the exposed surfaces of conducting-sheets placed one upon another with a sheet of non-conducting material having its surfaces coated with an adhesive agent between them, of means for applying pressure to said sheets while said adhesive agent is in a plastic condition. 125

11. The combination, with means for heating metallic sheets placed one upon another with an adhesive agent and a non-conducting material between them, of means for applying pressure to said sheets while said adhesive agent is in a plastic condition, substantially as described.

In witness whereof we have hereunto set our hands this 27th day of October, 1903.

FREEMAN C. ROBINSON.

JOHN F. JACOBY.
